EDMUND LICHTENSTEIN, OF BERLIN, GERMANY.

METHOD OF COPYING LETTERS.

1,049,741.

Specification of Letters Patent. Patented Jan. 7, 1913.

Application filed March 29, 1911. Serial No. 617,725.

To all whom it may concern:

Be it known that I, EDMUND LICHTENSTEIN, subject of the German Emperor, residing at Berlin, Germany, have invented 5 new and useful Improvements in Methods of Copying Letters, of which the following is a specification.

The present invention relates to an improved method of copying letters and the like written or printed matter, the invention 10 consisting in an improvement which may be applied to or carried out with copying machines of known types. These machines are to some extent dependent for their satis- 15 factory operation upon the nature of the original letters and the like to be copied, matter which has been written or printed in copying ink for any length of time not making such a good copy as freshly written 20 or printed matter. According to the present invention this difficulty is overcome by heating the sheets which are to be copied while they are in the copying machine. The effect of this heating is surprising. The heating 25 can be effected in a variety of ways. It may advantageously be effected by the copying roller itself, by which the original letter or the like is carried onto and held against the damp copying paper. In this case the heating 30 is effected by a suitable heating device within the roller itself.

One embodiment of the invention is illustrated diagrammatically in the drawing.

The copying paper *p* from roller *a* runs 35 through a water receptacle *b*, into which it

is led in any suitable manner, as by means of a guide *c*. It then runs between a roller *d* and a roller *e*. The paper then passes between roller *e* and the copying roller *g* which is heated in any suitable manner, as for example, by means of a gas burner positioned within the roller. The copying paper then runs between rollers *h* and *i* to the cutting device. The paper to be copied is inserted as indicated by the arrow between the copying roller *g* and the copying paper, whereby the paper to be copied will be in engagement with the heated roller during the copying process.

Having now particularly described and ascertained the nature of my said invention, and in what manner the same is to be performed, I declare that what I claim is:—

The herein described method of copying letters which consists in running the sheets 55 containing the matter to be copied and the moistened copying paper over the copying roller, the sheet containing the matter to be copied being interposed between the copying paper and the roller, and heating the roller 60 from within, whereby the sheets will be subjected directly to the action of heat while passing over the roller.

In testimony whereof I have signed my name to this specification in the presence of 65 two subscribing witnesses.

EDMUND LICHTENSTEIN.
